UNITED STATES PATENT OFFICE.

FREDERICK O. PERKINS, OF NEW YORK, N. Y., ASSIGNOR, BY MESNE ASSIGNMENTS, TO THE ANDREW JERGENS COMPANY, OF CINCINNATI, OHIO, A CORPORATION OF OHIO.

SHAVING-STICK HOLDER.

Application filed January 27, 1922. Serial No. 532,131.

To all whom it may concern:

Be it known that I, FREDERICK O. PERKINS, a citizen of the United States of America, and a resident of New York, in 5 the county of New York and State of New York, have invented a new and useful Improvement in a Shaving-Stick Holder, of which the following is a specification.

My invention relates to that class of devices used to hold a stick of shaving soap and into which and from which the soap may be inserted and removed.

An object of my invention is to provide a device of this type wherein the stick of soap is positively precluded against movement in relation to the holder.

Another object of my invention is to provide a device of this type, adapted to preclude accidental separation of the soap from 20 the holder.

Another object of my invention is to simplify and facilitate the removal of the stub of soap left in the holder after the major part of the soap has been used.

25 These and other objects are obtained by means described herein and disclosed in the accompanying drawings, in which:

Fig. 1 is a front elevation of a holder embodying my invention, and having a stick 30 of soap mounted upon it.

Fig. 2 is an enlarged sectional view on line 2—2 of Fig. 1.

Fig. 3 is a perspective view of a cup forming a detail of my invention.

35 The device embodying my invention consists of a holder comprising a cap 1 within which is removably contained a cup 2, the cup being adapted to accommodate the lower end of the stick of shaving soap 3.

40 The cap 1 comprises a base 23 from which extends a cylindrical flange 4, the upper end of which is turned inwardly, whereby a bead 5 is formed about the cylindrical wall of the cap. Screw threads 6 are formed

45 upon the outer surface of the cylindrical wall of the cap and are adapted to be engaged by the screw threads 7 formed on the interior surface of the cylindrical case

50 8 which is adapted to be placed over the stick of soap. The base of the cap has a cylindrical perforation 9 through which a thumb or finger may be inserted and be brought into engagement upon the lower or outer face 10 of the base 12 of the cup

2 when said cup is mounted upon the cap. 55 The cup comprises a base 12 from which extends a cylindrical wall 13 having slits 14 formed in it, said slits extending longitudinally of the cylindrical wall 13, whereby spring fingers 15 extending from the base 12, are formed. Fingers 15 are spaced from one another by the aprons 24 formed in the wall 13, as shown in Fig. 3. The upper ends of the fingers are turned inwardly, whereby radially extending lugs 16 60 are formed at the upper ends of the fingers. The fingers are corrugated intermediate their upper ends and lower ends whereby each finger has formed in it a pair of outwardly extending ridges 17 and 18 and between 65 which ridges is formed an inwardly extending ridge 19. Grooves 20 are formed in the outer walls of the fingers intermediate the ridges 17 and 18. These grooves 20 are disposed at such a place that when the base 70 of the cup is brought into engagement upon the inner face 21 of the base of the cap, the bead 5 formed on the cap will lie in the groove 20. The lugs 16 on the fingers are of 75 such length that their inner ends must enter into the stick of soap in order that the bead on the cap may enter the grooves on the fingers, thereby positively securing the soap in the cup. The ridges 17 and 18, which in the assembled condition of the holder, lie 80 on opposite sides of the bead 5, preclude accidental separation of the cup and cap. When it is desired to remove the cup from the cap, a thumb or finger is inserted through 85 the perforation in the cap and the pressure 90 exerted upon the bottom of the cup causes the lower ridges 17 to be sprung by the bead on the cap, thereby permitting withdrawal of the cup from the cap. The fingers are released from their grip upon the soap by 95 grasping the upper ends of the fingers and moving them away from the soap, whereupon the stub of soap remaining in the cup, may be removed therefrom.

What I claim is:

1. In a holder of the class described the combination of a cap comprising a cylindrical flange and a bead formed on the flange, a cup adapted to be inserted in the cap and comprising a base, fingers extending from the base, and lugs formed on the fingers adapted to enter a shaving stick disposed upon the base of the cup, the bead

on the cap being adapted to engage the fingers so as to preclude separation of the lugs from the stick.

2. In a holder of the class described the combination with a cap comprising a perforated base, a cylindrical flange extending from the base, and a bead formed at the free end of the flange, of a cup adapted to be inserted in the cap and comprising a base adapted to form a closure for the perforation in the cap, and means on the cap adapted to enter a shaving stick, the bead on the cap resisting withdrawal of the last mentioned means.

15 3. In a holder of the class described the combination with a cap comprising a base, a flange extending from the base, and a bead formed at the free end of the flange, of a cup adapted to be inserted in the cap and comprising a base, fingers on the base extending in substantial parallelism, lugs at the free ends of the fingers overlying the base of the cup, and a pair of outwardly extending ridges formed between the ends 20 of the fingers and between which the bead is adapted to lie when the cup is disposed within the cap.

4. In a holder of the class described the combination with a cap comprising a perforated base, a flange extending from the base, and a bead formed at the free end of the flange, of a cup adapted to be inserted in the cap and comprising a base adapted to form a closure for the perforation in the base, fingers extending from the base of the cup in substantial parallelism with the flange, lugs at the free ends of the fingers overlying the base of the cup, the fingers having grooves intermediate their ends in 35 which the bead may engage when the cup is inserted in the cap.

5. In a holder of the class described the combination with a cap comprising a perforated base, a flange extending from the base, and a bead formed at the free end of the flange, of a cup adapted to be inserted in the cap and comprising a base adapted to form a closure for the perforation in the base, fingers extending from the base of the cup in substantial parallelism with the flange, lugs at the free ends of the fingers 45

overlying the base of the cup, and a pair of ridges formed on the fingers intermediate their ends between which the bead is adapted to lie when the cup is inserted in the cap. 55

6. In a holder of the class described the combination with a cap comprising a base, a flange extending from the base, and a bead formed at the free end of the flange, of a cup adapted to be inserted in the cap and comprising a base, fingers on the base extending in substantial parallelism, lugs at the free ends of the fingers overlying the base of the cup, the fingers having formed in them intermediate their ends, grooves within which 60 the bead is adapted to lie when the cup is inserted in the cap.

7. In a holder of the class described the combination with a cap comprising a perforated base, a flange extending from the base and carrying an inwardly turned bead at the free end thereof, a cover having an open end, means on the open end of the cover and complementary means on the flange of the cap for mounting the cover on the cap, a cup adapted to be inserted in the cap and to form a closure for the perforation in the cap, comprising a base, fingers extending from the base, lugs at the free ends of the fingers overlying the base of the cup, and means 70 on the fingers for removably mounting the cup in the cap.

8. In a holder of the class described the combination of a cup and a cup shaped cap of substantially equal depth, the cap adapted to receive and seat the cup and having a central opening for permitting access to the cup for ejecting the cup from the cap, the cup comprising fingers substantially concentric with the side walls of the cap and the 75 cup and terminating adjacent the upper edge of the cap when the cup is seated in the cap, and a bead structure at the upper edges of the cap and fingers retaining the upper ends of the fingers in gripping engagement upon a semi-plastic stick received within the cup, and for holding the cup within the cap. 80 95

In testimony whereof, I have hereunto subscribed my name this 10th day of January, 1922.

FREDERICK O. PERKINS.
